United States Patent Office

Des. 214,395
Patented June 10, 1969

214,395

AUXILIARY VEHICLE LAMP

Hugo Magi, Etobicoke, Ontario, Canada, assignor to
Dominion Auto Accessories Limited, Toronto, Ontario,
Canada

Filed July 15, 1968, Ser. No. 12,754

Claims priority, application Canada June 8, 1968

Term of patent 14 years

Int. Cl. D26—03

U.S. Cl. D48—32

FIGURE 1 is a perspective view of an auxiliary vehicle lamp showing my design, taken from a forward vantage point;

FIGURE 2 is a side perspective view of the device of FIGURE 1 taken from a slightly raised vantage point, the side opposite that shown being the same in appearance; and

FIGURE 3 is a perspective view of the device of FIGURE 1 taken from a rearward vantage point.

I claim:

The ornamental design for an auxiliary vehicle lamp, as shown and described.
